UNITED STATES PATENT OFFICE.

JOHN E. OSMER, OF OWOSSO, MICHIGAN, ASSIGNOR OF ONE-HALF TO WILLIAM F. BYERLY, OF OWOSSO, MICHIGAN.

DRAFT DEVICE FOR LOCOMOTIVES.

Application filed February 28, 1921. Serial No. 448,445.

To all whom it may concern:

Be it known that I, JOHN E. OSMER, a citizen of the United States, residing at Owosso, in the county of Shiawassee and 5 State of Michigan, have invented certain new and useful Improvements in Draft Devices for Locomotives, of which the following is a specification.

The invention pertains in general to locomotives, and has more particular reference 10 to means for creating an induced draft in the locomotive stack.

The general aim of the invention is to increase the efficiency of locomotives by 15 maintaining a substantially constant draft upon the fire in the fire box to insure the maintenance under varying conditions of what is commonly known as a "good, free steaming locomotive boiler."

More specifically stated, the invention has 20 for its object the provision of means operable automatically, in the intervals occurring between the blasts of exhaust pressure in the operation of the locomotive, to effect the discharge, during such intervals, of supplemental blasts of pressure fluid coacting with the exhaust blasts to create a 25 constant draft in the locomotive stack with the result that the fire in the fire box is maintained incandescent irrespective of the speed of travel of the locomotive.

A further object of the invention is to provide means of the character stated which is also capable of manual control.

The objects of the invention thus generally stated, together with other and ancillary advantages will be apparent as the description proceeds.

In the accompanying drawings, Figure 1 40 is a side elevation partially diagrammatic, of a locomotive equipped with my invention. Fig. 2 is a fragmentary transverse sectional view on an enlarged scale through the smoke box of the locomotive. Fig. 3 is a fragmentary elevation section taken substantially in the same plane as Fig. 2, but on an enlarged scale to show details of construction.

Referring first to Fig. 1, 7 designates a 50 locomotive, 8 the fire box of the locomotive, and 9 one of the cylinders connected by means of a dry pipe 10 with the boiler. At the forward end of the boiler is the smoke box 11 having a stack 12.

13 (Fig. 2) is an exhaust nozzle into

which exhaust steam or pressure is discharged from the cylinders 9 by way of exhaust passages 14. Said nozzle provides a continuation of said exhaust passages and discharges in turn into the stack 12. Preferably the exhaust nozzle is equipped with a valve member 16 of the general type disclosed in my copending application Serial No. 355,595, filed February 2, 1920. This valve member comprises a central conical portion 17 having radially projecting wings 18 by means of which it is guided for up and down movements in the nozzle. Such movements are effected by pressure fluid admitted from a suitable source of pressure fluid supply, as by way of a pipe 19 and passage 20, 21, and acting directly upon the valve member. This pressure is such that together with the exhaust pressure discharged into the nozzle it lifts the valve 75 member from off its seat 22. The flow of pressure fluid to the valve 16 may be automatically controlled (in a manner not shown) so that when the locomotive throttle is open, pressure fluid is admitted to the 80 valve to raise it, and a piston 23 acting in a chamber 24 in the valve member serves to prevent sudden movements or a fluttering of the latter; all as more fully set forth in said copending application.

85 Preferably the exhaust nozzle 13 has at its upper end a separately formed portion or crown 25 made at its lower end of a diameter somewhat greater than the diameter of the nozzle and restricted at its upper end to a diameter substantially equal to that of the nozzle. The exhaust valve 16 preferably is correspondingly shaped at its upper end, whereby the pressure discharging from the nozzle assumes the form of a ring which 90 enters the stack 12 in such a way as to fill it more completely than is possible in the case of a single central jet discharged into the stack. This intensifies the draft created in the stack by the exhaust blasts.

100 When a locomotive is operating under a heavy load, as when working on an up grade, and when it is operating slowly as when it is being brought to rest, the intervals occurring between successive blasts of exhaust 105 pressure from the cylinders to the stack are of such duration that an inrush of cold air to the fire box is permitted which seriously detracts from the efficiency of the locomotive.

110 In order to prevent such inflow of cold

air to the fire box, I have provided means automatically operable during the intervals occurring between the blasts from the cylinders to effect the discharge of supplemental blasts of pressure fluid, complementing the exhaust blasts so that at all times the flow of pressure into the stack is maintained, thus overcoming the difficulties heretofore experienced in this connection.

10 The means herein shown for accomplishing this object is a means for discharging pressure fluid into the stack which means is controlled automatically by the pressure in the exhaust passage or passages leading from 15 the locomotive cylinder or cylinders, or manually; and preferably the pressure fluid is in the form of live steam conducted from the boiler to a jet discharging into the stack.

17 Referring now to Figs. 2 and 3, 26 designates a chamber communicating with the exhaust passage, being formed on one side of the exhaust nozzle 13 by means of a casting 27. 28 is a piston operating in said chamber and connected by means of a rod 29, a bell 25 crank lever 30 and a rod 31 with a valve member 32 operable to control the flow of pressure fluid to jets 33 mounted in the nozzle crown 25.

30 The rod 29 is slidable at one end through the casting 27, and at its other end moves through a bearing 34 secured upon the inner wall of the smoke box 11, which latter is provided with a stuffing box 35. The bell crank 30 may be pivoted in a bracket 36 secured upon the outer side of the smoke box.

40 The valve member 32 carried by the upper end of the rod 31 is mounted within a valve casing 37 having suitable means 38 providing a tight joint around the valve rod 31. Said casing has an inlet opening 39 provided at its inner end with a seat 40 for the valve member 32, and communicating by way of a pipe line 41 with a source of pressure fluid supply. Herein such source of supply is the locomotive boiler 7 (Fig. 1), the pipe line extending rearwardly along the exterior of the boiler and into the cab, where it is provided with a suitable manually operable valve 42, and is tapped into the boiler. The valve casing 37 (Fig. 3) also has an outlet opening 43 communicating by way of a pipe 44 with the jets 33. The latter as above indicated are carried by the crown 25 on the exhaust nozzle, which is cast to provide an annular channel 45 with which the pipe 44 communicates, said channel having one or more upwardly extending pipe sections each constituting a jet 33. A suitable stuffing box 46 is provided upon the inner wall of the smoke box around the pipe 44.

60 It will be observed that the valve mechanism and certain of the associated parts are located exteriorly of the smoke box. This construction is obviously advantageous since

it permits of convenient access to the working parts for the purposes of repair and the like. Within the nozzle 13 and above the chamber 26 there may be provided a hood 47 projecting inwardly a short distance into the nozzle. This hood it will be seen serves 70 to restrict the flow of exhaust pressure through the nozzle so that its effect upon the piston 28 is increased, and the same is true of the exhaust valve 16 in the nozzle.

75 For the purpose of enabling the piston 28 to move with relative freedom and smoothness, while at the same time preventing fluctuations thereof, I provide a suitable vent from the piston chamber 26 to the exterior of the smoke box. Thus, in Fig. 80 3, I have shown a duct 48 formed in the piston rod 29, and opening at one end into the chamber 26 as at 49 and at its other end to the atmosphere as at 50.

85 The operation of the device will, it is thought, be apparent. With the valve 42, in the pipe line 41 leading from the boiler open, the valve member 32 will in the absence of sufficient pressure upon the piston 28 be forced into its open position. A blast 90 of live steam thus passes to the jet 33 and thence into the stack 12. When, however, pressure within the exhaust nozzle increases, as during the occurrence of the discharge 95 of exhaust pressure from one of the cylinders, such pressure acting upon the piston 28 actuates the valve member 32 against the pressure of the live steam, the surface of the valve member being relatively small, 100 whereby the flow of steam to the jet 33 is cut off. It will thus be observed that when either cylinder is discharging into the exhaust nozzle the flow of steam to the jet 33 is cut off; and during the intervals between 105 the blasts of exhaust pressure into the nozzle, blasts of live steam are discharged into the stack. Thus, a substantially constant flow of pressure into the stack is effected so that a constant draught is maintained upon the fire in the fire box. Accordingly 110 the fire in the fire box will be maintained incandescent at all times,—that is to say, whether the locomotive is traveling at a relatively high rate of speed, is traveling very slowly under a heavy load, or is at rest,—the discharge of pressure fluid from the jet 33 into the stack serving to supplement or complement the discharge 115 of pressure from the exhaust nozzle into the stack. The result is that smoke flowing from the stack is substantially eliminated and the efficiency of the locomotive correspondingly increased so that heavier trains 120 are capable of being hauled.

125 Obviously by the control of the valve 42, the flow of steam to the stack may be controlled at will.

While I have illustrated and described

the invention with considerable particularity, and with reference to one embodiment only thereof, it will be understood that the invention is not limited to the particular

of pressure fluid to the stack, said means comprising a valve actuating member responsive to the pressure in the exhaust passage. 65

5 construction and arrangement of parts employed, it being contemplated that various changes may be made by those skilled in the art without departing from the spirit and scope of the invention as expressed in 10 the appended claims. I desire to particularly point out that the location of the controlling mechanism for the pressure fluid actuated valve 32 may be either within or without the smoke box as may be desired.

6. In a locomotive, the combination of an exhaust passage for receiving the intermittent discharges or blasts of exhaust pressure from the locomotive cylinder or cylinders, a stack, and means controlled by the pressure in the exhaust passage to discharge pressure fluid into the stack during the intervals occurring between said blasts, said means comprising a conductor for pressure fluid, and pressure-actuated valve means for controlling said conductor. 70

15 It should also be understood that the invention is not limited to any particular form of exhaust nozzle since the actuating piston for the valve 32 may obviously receive pressure from any point in the exhaust passage which may seem desirable.

7. In a locomotive, the combination of an

I claim as my invention:

1. In a locomotive, the combination of a cylinder, an exhaust passage, a stack, and pressure fluid discharge means adapted to complement the intermittent blasts into the stack from the locomotive cylinders to effect a substantially constant discharge of pressure fluid into the stack irrespective of the speed of travel of the locomotive. 20

8. In a locomotive, the combination of an

25 2. In a locomotive, the combination with a cylinder having exhaust passage, a stack, and pressure fluid discharge means automatically controlled to effect the discharge of fluid pressure into the stack when the cylinder is not discharging through the exhaust passage into the stack.

9. In a locomotive, the combination of a

30 3. In a locomotive, the combination of an exhaust passage for receiving the intermittent discharge of exhaust pressure from the locomotive cylinders, a stack, and means operative to discharge pressure fluid into the stack between blasts discharging from the exhaust passage into the stack, whereby to complement such exhaust blasts to produce a constant flow of pressure fluid to the stack. 45

10. In a locomotive, the combination of a

35 4. In a locomotive, the combination of an exhaust passage for receiving the intermittent discharge of exhaust pressure from the locomotive cylinders, a stack, and means operative to discharge pressure fluid into the stack between blasts discharging from the exhaust passage into the stack, whereby to complement such blasts to produce a constant flow of pressure fluid to the stack, said 50 means being controlled by the pressure in the exhaust passage. 55

11. In a locomotive, the combination of a

40 5. In a locomotive, the combination of an exhaust passage for receiving the intermittent discharge of exhaust pressure from the locomotive cylinders, a stack, and means operative to discharge supplemental blasts of pressure fluid into the stack between blasts of exhaust pressure, whereby to complement the exhaust blasts to produce a constant flow

12. In a locomotive, the combination of a

13. In a locomotive, the combination of a

14. In a locomotive, the combination of a

15. In a locomotive, the combination of a

16. In a locomotive, the combination of a

17. In a locomotive, the combination of a

18. In a locomotive, the combination of a

19. In a locomotive, the combination of a

20. In a locomotive, the combination of a

21. In a locomotive, the combination of a

22. In a locomotive, the combination of a

23. In a locomotive, the combination of a

24. In a locomotive, the combination of a

25. In a locomotive, the combination of a

26. In a locomotive, the combination of a

27. In a locomotive, the combination of a

28. In a locomotive, the combination of a

29. In a locomotive, the combination of a

valve means operable by the pressure in the exhaust passage to cut off automatically the flow of steam through the conductor.

11. In a locomotive, an exhaust nozzle providing a passage for pressure fluid intermittently discharged from the locomotive cylinders, a chamber communicating with said passage, a piston in said chamber, means for discharging blasts of pressure fluid during the intervals occurring between the blasts from the cylinders, and a valve for controlling the discharge of pressure fluid operatively connected with said piston.

12. In a locomotive, an exhaust nozzle providing a passage for pressure fluid intermittently discharged from the locomotive cylinders, a chamber communicating with said passage, a piston in said chamber, means for discharging blasts of pressure fluid during the intervals occurring between the blasts from the cylinders, a valve for controlling the discharge of pressure fluid operatively connected with said piston, and a passage of restricted cross-sectional area establishing communication between said chamber and the atmosphere.

13. In a locomotive, a smoke box, an exhaust nozzle in said smoke box providing a passage for pressure fluid intermittently discharged from the locomotive cylinders, a chamber at one side of said nozzle communicating with said passage, a piston in said chamber, means for discharging blasts of pressure fluid during the intervals occurring between the blasts from the cylinders, said means comprising a conductor communicating with a source of pressure fluid supply, valve means located externally of the smoke box for controlling said conductor, and an operative connection between said piston and said valve means.

14. In a locomotive, the combination of an exhaust nozzle providing a passage for the discharge of exhaust pressure from the locomotive cylinder or cylinders, valve means for said passage operable automatically to permit the discharge of exhaust pressure from the passage but tending to restrict the passage, means for discharging pressure fluid during the intervals occurring between discharges from said passage, said means being automatically controlled by the pressure in the exhaust passage and including a pressure responsive means communicating with said passage below said valve means.

15. In a locomotive wherein blasts of exhaust pressure are intermittently discharged from a cylinder or cylinders into a stack, the combination of means controlled by such intermittent blasts to effect the discharge of supplemental blasts of pressure fluid into the stack whereby to produce a constant draft in the stack, said means being adapted normally to permit the discharge of pressure fluid and to cut off the discharge of

such pressure fluid during the blasts of exhaust pressure from the cylinder or cylinders into the stack.

16. In a locomotive, a smoke box, a stack, a nozzle intermittently discharging the exhaust steam into the stack, a live steam jet discharging into the stack, and a valve controlled by the pressure in said nozzle to effect the discharge of supplemental blasts of live steam through said jet in the intervals between the nozzle exhausts.

17. A draft regulating device for locomotives, comprising a stack, a nozzle discharging exhaust steam into the stack, a plurality of jets mounted on the end of said nozzle, a pipe connecting the jets with the locomotive boiler, valve means manually operable from the locomotive cab to open and close said pipe, and a valve controlled by the pressure in said nozzle operable when the first valve is open to effect the discharge of live steam through said jets in the intervals between the discharge of exhaust steam.

18. A draft regulating device for locomotives, comprising in combination with a stack and an exhaust passage discharging exhaust steam into the stack, of a jet also arranged to discharge into the stack and connected with the locomotive boiler, a valve for controlling the flow of steam from the boiler to said jet, and means automatically opening and closing said valve in accordance with the pressure in the exhaust passage, said means comprising a pressure-responsive member operatively connected with said valve whereby when exhaust occurs said valve is moved to close said pipe and in the intervals between exhausts said valve is moved to open position.

19. A draft device for locomotives, comprising a pressure-responsive member arranged so as to be subject to pressure within the exhaust passage, a means connected with a source of fluid under pressure and adapted to discharge such fluid into the locomotive stack, and valve means actuated by said pressure-responsive member whereby to control the flow of such fluid under pressure to the stack.

20. A draft device for locomotives, comprising a pressure-responsive member arranged so as to be subject to pressure within the exhaust passage, a means connected with a source of fluid under pressure and adapted to discharge such fluid into the locomotive stack, and valve means actuated by said pressure-responsive member whereby when exhaust occurs the flow of the fluid under pressure to the stack is cut off and in the absence of exhaust pressure the fluid under pressure is permitted to flow into the stack.

In testimony whereof, I have hereunto set my hand.

JOHN E. OSMER.
